UNITED STATES PATENT OFFICE.

RANDALL MITCHELL, OF DETROIT, MICHIGAN.

PADDLE-WHEEL.

SPECIFICATION forming part of Letters Patent No. 575,845, dated January 26, 1897.

Application filed September 11, 1896. Serial No. 605,477. (No model.)

To all whom it may concern:

Be it known that I, RANDALL MITCHELL, a citizen of the United States, residing at Detroit, in the county of Wayne and State of Michigan, have invented a new and useful Improvement in Paddle-Wheels, which improvement is fully set forth in the following specification and accompanying drawings, in which—

10 Figure 1 is a rear view of my improved submerged paddle-wheel; Fig. 2, a side elevation. Fig. 3 is a horizontal section on the line $\alpha\alpha$ of Fig. 1; Fig. 4, a detail view.

15 My invention pertains to improvements in paddle-wheels for steam vessels; and my object is to provide a simple, practical, and durable device, inexpensive in construction, effective in operation, and easily controlled by an officer or outlook in charge of a vessel without stopping or otherwise interfering with the operation of the engines.

20 The peculiar construction and exceptional advantages of the invention will be apparent by referring to the accompanying drawings, in which—

A represents the hull of a vessel, provided on its outer side with a recess 2 of the required dimensions and protected by a metal plate 3. The paddles 4 and 5 are fixed at 30 right angles each to the other and have their inner ends connected by a rod 6, adapted to rotate in a sleeve 7, having a lateral right-angled extension 8 attached to the outer end of the wheel-shaft 9, which is journaled in a 35 stuffing-box 10. A circular metal plate 11 is rotatably attached to the stuffing-box, its outer border being in close engagement with the inner edge of a circular opening in the metal plate 3. A circular cam 12 is integrally 40 attached at one side to the plate 11, as at 13, its opposite side being connected therewith and supported by interposed bars or posts 14. The paddles are provided near their inner ends with antifriction-rollers 15. A sprocket- 45 wheel 16 is fixed on the stuffing-box 10, and connected by a chain belt to a similar wheel 17, journaled in the upper part of the recess 2. The inner extremity of the shaft of the 50 wheel 17 carries a lever 18, having at its upper end a latch adapted to adjustably engage a notched segment.

The operation of the device will now be described. It will be observed that the position of the lever 18, acting through the sprocket-wheel and connecting-chain, governs the position of the circular cam-plate, which in turn controls the relative position of the paddles. In the drawings it will be seen that the lower paddle is in operative position, while the upper, being transversely disposed, presents its edge to the water and is therefore inoperative. These positions are maintained while the rollers of both paddles are traveling over the plane sections 19 and 20 of the surface of the cam, the inwardly-curved sections being 55 indicated by shaded lines. When the lower paddle approaches the surface of the water, the rollers will engage the outwardly-curved section of the cam, and the roller of the upper paddle being relieved by passing over the oppositely-inclined section the paddles will necessarily turn until their former positions are 60 reversed.

Among the prominent advantages of the device the following may be enumerated: 65

The paddles being entirely submerged are not exposed to injury from floating timber or other obstructions.

The progress of the vessel is easily and 70 promptly controlled by the lever in the hands of the officer on watch. Being first to discover danger ahead, he can instantly reverse the motion of the wheels by changing the position of the circular cam without waiting to signal the engineer to stop and reverse the 75 engines. The time thus saved will in many instances avert disastrous collisions.

In navigating narrow and crooked streams, or when approaching a dock or landing, the motion of either wheel may be retarded or 80 stopped, as desired, for the time being.

A vessel may be held in a fixed position against a current or head-wind to permit an exchange of signals with other vessels or parties on shore whenever desired. All these and 85 other desirable performances are executed without the coöperation of the engineer.

It will be furthermore understood that if 90 an increase of power should make an increase of paddle-surface desirable a series of shafts 95 may be furnished with paddles and operated in conjunction.

A war-steamer thus provided might lose a number of paddles while under fire without being disabled.

What I claim as new is—

- 5 The combination with the wheel-shaft and the herein-described recess in the side of a vessel, of the submerged paddles, fixed at right angles each to the other, and rigidly united by a shaft journaled in a sleeve having a right-angled extension attached to the wheel-shaft; the disk rotatably attached to the stuffing-box of the wheel-shaft, the circular cam-plate attached to the disk and adapted to engage anti-friction-rollers mounted on the shoulders
- 10

of the paddles; the sprocket-wheels, the belt or chain connecting the same and the latch-lever whereby the feathering action of the paddles may be instantly reversed or their relative positions otherwise adjusted as desired, substantially as described.

In testimony that I claim the foregoing I have hereunto set my hand, this 20th day of August, 1896, in the presence of witnesses.

RANDALL MITCHELL.
